UNITED STATES PATENT OFFICE.

THOMAS R. ROSIER, OF SAN JOSÉ, CALIFORNIA.

FLAXSEED-CLEANER.

SPECIFICATION forming part of Letters Patent No. 324,275, dated August 11, 1885.

Application filed March 19, 1885. (No model.)

To all whom it may concern:

Be it known that I, THOMAS R. ROSIER, a citizen of the United States, residing at San José, in the county of Santa Clara and State 5 of California, have invented new and useful Improvements in Flaxseed-Cleaners, of which the following is a specification, reference being had to the accompanying drawings.

My invention relates to an improvement in 10 flaxseed-cleaners; and it consists in the peculiar construction and combinations of devices that will be more fully set forth hereinafter, and particularly pointed out in the claims.

15 In the accompanying drawings, Figure 1 is a side elevation of a machine embodying my invention. Fig. 2 is a vertical longitudinal sectional view of the same.

A represents a rectangular frame, in one end 20 of which, near its upper side, is journaled a transverse shaft, B, to which is secured a blower, C, that works in a case, D. To one end of this shaft is secured a spurred pinion, E, which meshes with a spurred wheel, F, and 25 a larger driving-wheel, G, which wheels are journaled on projecting spindles that are secured to the frame.

H represents a shoe, the sides of which are 30 in openings that are made in the sides of the frame. The shoe is suspended in the frame by rods I, and is connected to the pinion E by a rod, h. When the shaft B is rotated, the shoe is reciprocated. In the upper inner end of 35 the shoe is placed an inclined feed-board, K, which is beneath the opening in the bottom of the hopper L, that is secured to the upper side of the frame, and in the shoe, above the lower side of the board K, is journaled a bar, M, having projecting teeth m, which extend 40 into the hopper, stirring the flaxseed therein, and thus facilitating its passage onto the inclined feed-board K. In the shoe is located an inclined sieve, N, the upper end of which 45 communicates with the board K, and the lower end of which projects out beyond the shoe, as shown. This sieve can be secured at any desired angle in the shoe by means of the bolts n and the series of openings n', that are made in the sides of the shoe. Vertical openings h' 50 are made in the sides of the shoe, near the lower end thereof.

O represents a rack that is composed of lon-

itudinal slats o and transverse cross-bars o'. This rack bears against the under side of the sieve N, being supported by a cross-beam, P, 55 the ends of which project out through the openings h' in the shoe and slide upon vertical rods R, which are secured in blocks r, that are bolted to the sides of the frame. Coiled springs S are placed on the rods R and bear against 60 the under side of the beam P, and thus keep the rack O in contact with the under side of the sieve N. The lower ends of the springs are supported in stirrups S', that are suspended by chains S' from hooks S'', that are secured to the upper blocks, r. The tension of 65 the springs on the ends of the beam P may be regulated by detaching the chains from the hooks and securing them thereto by different links.

T represents a rack that is similar in construction to the rack O, and that bears against the upper side of the sieve N. This rack is secured by chains t to the sides of the frame. By this construction it will be understood that 75 while the sieve N reciprocates, the racks which bear against it remain practically immovable. The function of the upper rack is to force the flax through the sieve and prevent it from accumulating in bunches and sliding down and 80 off the sieve, and to force the large seeds and foreign substances rapidly down and off the sieve. The lower rack is for the purpose of keeping the sieve from clogging.

Beneath the sieve N, and secured in the vi- 85 brating shoe, is an inclined grain-board, U, the lower end of which projects slightly beyond the outer side of the shoe, as shown.

V represents a frame that is hinged in the frame A, near the lower side thereof, as at v. 90 This frame is inclined in the opposite direction to the sieve N, and can be inclined to any desired angle by means of a winch, W, that is journaled in the frame A. The free end of the frame V is connected to the winch by 95 hoisting-cords w, and to one of the projecting ends of the winch, on the outer side of the frame A, is fixed a ratchet-wheel, w', with which engages a pivoted pawl, w''.

In guideways v', formed in the inner sides 100 of the frame V, is secured a reciprocating screen, X, the meshes of which are finer than those of the sieve N. To the outer upper end of the screen X is secured a board, X', which

projects beyond the frame A a suitable distance below the sieve N. A rock-shaft, Y, is journaled in the frame A, and has an arm, y, that is connected to the screen X by a connecting-rod, y'. One end of the rock-shaft has a crank-arm, y², that is connected to the gear-wheel F by a pitman, y³. An inclined board, Z, is secured in the frame A above the frame V. To the lower side of this board is secured to a piece of canvas, A', which bears upon the upper side of the screen X. The lower end of the canvas is secured to a bar, A², that is suspended beneath a cross-bar, v', of the frame V.

15 B' is a rectangular frame that is arranged under the screen X. This frame is supported by flat springs B², that are secured to it and to a cross-beam, v², of the frame V. In the frame B' are journaled a series of rollers, B³, that bear against the under side of the screen X.

20 As the screen reciprocates it is cleaned by the rollers. The function of the canvas A' is to prevent small seeds from rolling or bounding off the screen and to force them through the screen, while the flax passes between the screen and the canvas and is delivered at the lower end of the screen.

25 When the machine is in operation, the fan or blower forces a current of air through the frame or casing A in the direction indicated by the arrows in Fig. 2, and winnows the flax as it falls from the grain-board onto the screen X.

Having thus described my invention, I claim—

1. The combination of the frame or casing, 35 the reciprocating shoe, the sieve located in the shoe and adjustable therein, the cleaning-rack arranged under the sieve, the supporting-beam P therefor, passing through openings in the sides of the shoe, vertical rods R, passing 40 through the ends of the beam P, springs on the rods to support the beam P, stirrups S', suspending-chains S² and hooks S³, and means for supporting the hooks, the lower ends of the springs bearing on the stirrups, substantially 45 as described.

2. The combination of the frame or casing, the reciprocating shoe, the sieve located in the shoe and adjustable therein, the stationary cleaning-rack arranged under the sieve, a 50 supporting cross-beam therefor passing through openings in the sides of the shoe, vertical rods secured to the casing and passing through the ends of the cross-beam, springs on the rods to support the rack, and means 55 for regulating the tension of the springs, substantially as described.

In testimony that I claim the foregoing as my own I have hereto affixed my signature in presence of two witnesses.

THOMAS R. ROSIER.
